HAT FINISHING MACHINE

James H. Johnson, Columbus, Ohio

Application November 5, 1929. Serial No. 405,001

4 Claims. (Cl. 223—30)

My invention relates to improvements in hat finishing devices, especially for use by manufacturers and renovators and comprises the novel design, arrangement and combination of parts 5 hereinafter disclosed and claimed:

A first object of the invention is to produce a machine which will accomplish the complete finishing of felt and straw hats automatically, including both crowns and brims. These two operations have never been performed successfully 10 on one machine prior to creation of this design, since heretofore all brims have been finished manually by both hat manufacturers and renovators.

Another object is to provide a machine of few 15 parts, strong and durable which will meet every requirement of the operator. One that is simple in construction and carefully balanced so that the load on the motor will be at a minimum.

A further object is to furnish a device fitted for 20 interchangeable tools or applicators for singeing—sanding—brushing—rolling—sponging—luhring and ironing to provide finishes for different types of hats.

Another object of my invention is to put forth 25 a device mechanically fool-proof and one that can be disengaged instantly from the propelling element, that can be adjusted easily and quickly in varying the extent of movement and amount of 30 pressure applied and all with a minimum of exertion.

Another object of the design is to create a 35 simple mechanism which may be propelled by any power means and proper direct connected gear or belt and pulley reduction in the correct relation for the applicator to travel much slower than the hat block or brim flange.

Other advantages of this invention will be more 40 fully understood from the following clear and concise description considered in relation to the drawing in which similar numbers are used in the several views.

Figure 1 is a front view of my device shown 45 mounted on a bench board with the iron up on the hat crown in ironing position.

Figure 2 is a right side view of Figure 1 with the iron down on the hat brim.

Figure 3 is a top view or plan of Figure 2.

In the detailed construction illustrated, the 50 machine is attached to a supporting table or bench top 4 through which a revolving vertical spindle shaft 5 extends and on which is mounted adjustably either a hat crown block 6 or a flange stand 7 and brim block 8 according to which operation is to be applied to a hat. A horizontal

cam shaft 9 is shown below the table top and in proper relation to vertical shaft 5 to permit compact assembly of ordinary stock motor speed reduction gearing to provide a relative speed of one R. P. M. for the cam shaft to about 60 60 R. P. M. for the hat block shaft.

A cam member 10 is mounted on power shaft 9 and in axial contact with said cam is a roller 11 secured in walking beam member 12, which has a bearing support at 13 and a projecting part 65 14 extending upwards toward the table. A counter-weight 15 is cantilevered on beam 12 and is employed to hold contact between roller 11 and cam 10 except when intentionally lifted away. The bearing 13 is on the lower end of a 70 yoke member 16 which is securely fastened to the table top at 17 and 18 and extends through a slot and above the table to another bearing 19 on which is journalled a second walking beam 20. This beam has an integral extension 21 at right 75 angles to its other arm 20. A weight 22 counter-balances the arm 21 to which is hinged a member 23 at point 24, having a joint into which can be attached applicators such as the electric ironing member shown at 25. Said applicators having a semi-universal bearing connection or center of gravity support with arm 23. Another counter-weight for parts 23—24 and 25 is indicated at 26. An adjustably mounted spring is shown at 27 for varying the desired pressure 80 85 to be exerted by applicator member 25 and also to hold arm 23 back out of interference when not in use. This object is accomplished when spring 27 moves past center of hinge joint. 90

On the opposite end of walking beam 20 opposite portion 21 and approximately equally distant from the bearing point 19 is a slotted section 28 into which is connected and adjustably secured by a suitable clamp and handle a connecting rod 29 which joins beam 12 at bearing 14 95 with beam 20 at bearing 28.

One means is provided for limiting the downward travel of the iron 25 and also to hold the iron mechanism back out of motion while hat alone may revolve. This is shown at 30 100 which is a hand wheel or knob that can be easily pulled forward to compress the spring 31 which disengages tooth clutch member 32 from stationary clutch member 33 thereby allowing arm 34 on wheel shaft 35 to be turned into contact with lever beam 20 which will lock at such point as desired by reengagement of the clutch by release of spring 31. The walking beam 12 and roller 11 is then held away from cam 10 during part 105 or all of the strokes A—B and C—D. 110

The slot 28 is employed to permit slideable adjustment of connecting rod 29 in same to vary the distance to fulcrum bearing 19 which thereby varies the length of the applicator stroke.

5 When engaged in upper end of slot 28 near fulcrum point the connecting rod 29 moves the iron in an arc from A to B and when in lower end of slot or farther from fulcrum the movement is from C to D. This feature permits of the finishing of both hat crowns and brims on one machine.

In the operation of my hat finishing device, a hat that has been cleaned, dried and steamed is ready for finishing. The proper size crown block is fitted to a hat and both are locked on the spindle shaft 5. The applicator selected by operator to be employed first is then inserted and fastened into arm 23 which is brought into position against hat surface and proper pressure 15 adjusted through spring 27. Rod 29 is run up into upper end of slot 28 and tightened there. The hand wheel 30 is pulled and turned to move arm 34 and thereby fix limit of stroke against hat crown above line of brim or ribbon as desired. A switch controlling the motor which 20 operates shafts 5 and 9 is then closed and the hat finishing process is started. The handle on end of arm 23 facilitates the movement of said arm and applicator 25 away from the hat 25 through hinge 24 and spring 27 which holds same at rest while applicators are being changed. An electric ironing applicator 25 with temperature control switch can be used without danger of scorching the hat since the cam member 10 is so designed that movement is speeded up over 30 crown and slowed down over curved part and sides to avoid streaks or spiral markings on hat.

When the crown is completed, the hat block is removed and flange stand 7 and brim flange 8 40 replaces same. A luhring cloth is tightly drawn over hat brim and fastened securely. Rod 29 is moved to other end of slot 28 which limits applicator movement between points C and D. The counter-weight 15 operates at all times to hold 45 pulley 11 on cam 10 since at top of stroke on dead center with bearing 19, the weight 15 is farthest from fulcrum point and near a horizontal position.

When the applicator arm 23 is thrown back 50 to idle position at points A and C and held thereby arm 34 and clutch members 32 and 33, the weight 15 does not act and cam 10 revolves without contact with pulley 11 until arm 34 is again lowered. This feature permits the operation and 55

use of spindle shaft 5 when applicator mechanism is idle.

I am aware that the construction shown for illustration purposes may be modified in certain particulars to simplify manufacture without departure from the spirit and scope of the invention; therefore, I do not limit myself to the exact construction shown and described but what I claim and desire to secure by Letters Patent is:

1. In a hat finishing machine, an ironing tool 85 adapted to iron both the crown and the brim of a hat, a walking beam carrying a swinging ironing tool and a spring for drawing said swinging ironing tool toward the hat, means for actuating said walking beam including a lever and a cam for actuating the same, a link connecting said lever and the walking beam, the means connecting said link with the walking beam being adjustable whereby the stroke of the iron can be varied to iron either the crown or the brim. 95

2. In a hat finishing machine, an ironing tool 100 adapted to iron both the crown and brim of a hat, a walking beam carrying a swinging ironing tool on one arm thereof, means for actuating said walking beam including a lever and a cam for actuating the same, a link connected at one end of said last named lever and the other arm of the walking beam, said last named connection being adjustable whereby the stroke of the iron can be varied to iron either the crown or the brim. 105

3. In a hat finishing machine, an ironing tool 110 adapted to iron both the crown and the brim of a hat, a walking beam carrying said ironing tool on one arm thereof, means for actuating said walking beam including a lever, a cam for actuating the same, a link connecting said last named lever and the other arm of the walking beam, the last named connecting means being adjustable whereby the stroke of the iron can be varied to iron either the crown or the brim. 115

4. In a hat finishing machine, an ironing tool 120 adapted to iron both the crown and the brim of the hat, a walking beam having an iron carrying arm hingedly connected to an arm of said walking beam, said iron carrying arm to swing at right angles to the plane of movement of the walking beam, said iron hinged to rock on said last named arm, means for actuating said walking beam including a lever, a link adjustably connecting said lever and the walking beam to 125 vary the length of stroke of the iron, and a cam for actuating said lever.
